UNITED STATES PATENT OFFICE.

JOHN GEORGE POOL, OF LYNN, MASSACHUSETTS, ASSIGNOR TO
NATIONAL BUNG MANUFACTURING COMPANY, OF PORTLAND,
MAINE, A CORPORATION OF MAINE.

TOOL-GRINDING MACHINE.

No. 820,519.

Specification of Letters Patent.

Patented May 15, 1906.

Application filed April 29, 1905. Serial No. 258,047.

To all whom it may concern:

Be it known that I, JOHN GEORGE POOL, a citizen of the United States, and a resident of Lynn, in the county of Essex and State of Massachusetts, have invented a new and useful Tool-Grinding Machine, of which the following is a specification.

My invention relates more especially to the grinding of a cutting-tool such as is described in an application for United States Letters Patent, Serial No. 252,320, filed March 27, 1905, by Edward E. Elder and myself as joint inventors for an improvement in plug-cutting machines, in which application there is shown a hollow cylindrical cutting-tool having advancing cutting-points with retreating cutting-surfaces forming two V-like edges. To grind such a tool with a rotary grinder, it is desirable that the tool and grinder shall have such a movement with relation to each other that the surfaces to be ground shall be continuously presented thereto. To this end I have shown in the present embodiment of my invention a means for rotating the tool and also a means for giving it a reciprocating movement parallel with its axis in order that the V-shaped edges may be properly ground. With these features are combined means for automatically feeding the grinder and the tool with relation to each other, so as to keep them in operative position. There is also provided means for adjusting the machine to grind tools of different diameters and having differently-shaped cutting edges from those shown—that is, tools in which the distance from the tip of the point to the bottom of the V varies from o to that shown—that is, from a straight edge to a V-shaped edge even deeper than that shown. These and other novel details of construction will be explained in the following specification. Moreover, I have shown my invention embodied in a machine adapted to grind a cylindrical tool; but it will be apparent that it or certain of its features may be adapted to grind tools having a different cross-section.

My invention will be understood by reference to the drawings, in which—

Figure 1 is a rear view of a machine embodying my invention. Fig. 2 is a section taken just in rear of the front wall. Fig. 3 is an end view, the wall being broken away to

disclose the interior of the case. Fig. 4 is a sectional view on line 4 4 of Fig. 2. Fig. 5 is a vertical section on line 5 5 of Fig. 2, the gage being omitted. Fig. 6 is a vertical section on line 6 6 of Fig. 3. Fig. 7 is a vertical section on line 7 7 of Fig. 6, and Fig. 8 is a detail of the grinder-feed. Fig. 9 is a view in plan and elevation of the head on which the tool is mounted, showing the position of the registering and holding pin therein. Fig. 10 is a view in inverted plan and elevation of the tool, showing a registering hole therein and the position which it bears to the elevated point of the tool. Fig. 11 is a view in elevation of the links hereinafter lettered h h' , and Fig. 12 is a view in plan of the links hereinafter lettered h^4 h^4 .

A are the supports upon which is mounted the casing containing the various parts, the walls of the casing being marked a and the casing being provided with a top and bottom to keep the interior free from dust. Suitable doors or other openings are provided, so that the interior may be easily examined.

B is the main shaft, which passes through the machine and is suitably supported therein. It carries at one end fast and loose pulleys B' B^2 and at the other end a driving-pulley B^3 , from which the grinder C is rotated by a belt, and beyond it a cone-pulley B^4 , from which by means of a belt motion is given to the cone-pulley D' on the counter-shaft D. On the counter-shaft D is mounted a pinion d , which meshes with the gear d' on a stud d^2 , projecting from a boss d^3 on the inside of the casing. A pinion d^4 on the same stud d^2 is arranged to turn with the gear d' and meshes with the gear d^5 . The gear d^5 has pinned to it a bevel-gear d^6 , and both are mounted on a sleeve e, which carries a heart-shaped cam E and is mounted on a stud d^7 , projecting from one wall of the casing. A screw and washer d^8 hold the sleeve on the stud.

The tool-holder, as shown, comprises a shaft F, having a boss at its upper end, which rests upon a sleeve F', within which the shaft F rotates and by means of which the shaft is reciprocated in the direction of its axis. The sleeve passes up through an opening in the top of the case and is surrounded by a bushing a' . The lower part of the sleeve F' is supported upon the carriage H, as below de-

scribed. The shaft F projects below the sleeve F' and is provided with a collar x, which bears against the lower end of the sleeve F' and may be adjusted to prevent end motion of the shaft F in the sleeve F' by means of the set-screw x', (this arrangement also serves to compensate for any wear of these parts which may occur,) and is connected with a bevel-gear F² below the carriage H, which meshes with the bevel-gear d⁶ on the sleeve e, from which it gets its motion. To connect the bevel-gear F² and the shaft F, the bevel-gear is provided with a hub F³, which sets into a bearing G' in a frame G, which is bolted to the floor of the case. A collar f' on the hub F³ keeps it from rising in its bearing. The shaft F and hub F³ are connected by a spline and groove, so that the shaft will be rotated and may also be reciprocated. These two motions are necessary in order to present the tool to the grinder in such a way as to get the desired finished surface.

The tool may be mounted upon the shaft in any desired way. I prefer to make the shaft F hollow, so that any particles of emery and steel may fall through, and to use the passage also as a socket for the shank F⁴ of the tool-holding chuck. In such a case the shank F⁴ is provided with a longitudinal groove F⁵, preferably semicircular in cross-section, and a set-screw F⁶, having a hemispherical end, passes through the boss f and into the groove F⁵ and binds the shank F⁴ against both a twisting and a longitudinal movement. The chuck itself comprises a platform f², on which the tool stands and which is threaded about its periphery, and a nut f³, having a lip f⁴, which binds the tool f⁵ to the platform, (see Fig. 5,) this being a simple form of construction. In the upper surface of the platform f² and as near to its periphery as is practical I prefer to drill a hole in which I insert permanently a pin or dowel y, such pin or dowel being allowed to project above the surface of the platform f² about one-eighth of an inch. This pin or dowel I prefer to place so that the center of the pin and the center of the longitudinal groove F⁵ in the shank F⁴ shall lie in the same radial plane. In the bottom face of the tool or cutter f⁵ by means of a suitable jig a hole y' is drilled, which will correspond both in diameter and distance from center with the diameter and distance from center of the pin y in platform f². Furthermore, this hole y' is preferably drilled on a radial plane passing through the extreme points y² of the cutter f⁵. Now when the cutter is placed upon the platform for grinding the hole in the lower face of the cutter f⁵ is placed over the pin in the platform f², which thus when inclosed with the nut f³ serves to place it at once in proper rotary relation with the shaft F. The set-screw F⁶ in the upper end of the shaft F is so placed in relation to the

movements of the various parts of the machine that it shall lie on the side of the shaft F which is either nearest to or farthest from the grinder C when the sleeve F' is at the lowest point of its travel. The object of this arrangement will be described below.

The means for reciprocating the tool will now be described. Upon the side of the case to which the stud d⁷ is attached are also attached horizontal ways E', in which runs a slide E², suitable gibbs being provided to hold the slide therein. This slide is slotted, so that the stud d⁷ may pass through it, and it carries two rolls e' e², located to bear upon opposite edges of the cam E, so that the rotation of the cam will give a regular reciprocation to the slide E² without any lost motion. Upon the frame G, mounted on the bottom of the case, are horizontal ways g, in which runs a carriage H, held therein by gibbs g', this carriage H and the slide E² being connected to slide in unison, preferably in the following manner: The carriage H has pivoted to its front end a link h, which is part of an H-shaped frame, of which the link h', which is pivoted to the slide E², is another member, these two links being joined by a cross-bar h² near their middle. The parts h, h', and h² are a single casting in order to get the necessary rigidity, and this frame is pivoted by a rod h³ to a sleeve h⁶, from which project two parallel links h⁴ h⁴, integral with the sleeve, each link connecting as an integral part with a second and similar sleeve and by a similar rod supported between brackets h⁵, attached to the end wall of the case. Both of these sleeves h⁶ and both links h⁴ are a single casting. It is evident that this construction, composed as it is of but two castings, with its bearings in the same vertical plane with the points of application of both the power and work and each casting of such width as to completely fill the space between the bearings, together with the form of joints shown, must and does form a firm and rigid and theoretically perfect means of transmitting the motion of the slide E² across the intervening space to the slide H. The slide E² and the carriage H have a motion horizontally on the same plane and parallel to each other, working in the same time and direction and to the same distance. It is therefore evident that to connect these parts the pin h⁸ on the slide E² and also the similar fulcrum-screw on the carriage H must lie on the same horizontal plane, the vertical vibration of the links h h' due to radial action, being taken by the links h⁴ h⁴. The upper ends of the links h h' travel in a horizontal plane.

The tool is reciprocated vertically by means of the horizontal reciprocation of the carriage H in the following manner: Ways H' are pivotally attached to the sleeve F' (see Fig. 5) by means of screws H². In order to secure good mechanical construction and

proper rigidity in action, both of these ways H' consist of a single casting, being joined together by the substantial cross-bar shown at Z. (See Fig. 4.) This arrangement pre-
 5 serves at all times perfect alinement of the ways H', prevents any tendency of said ways to lag or bind in relation to each other, and also serves to positively prevent any tendency on the part of the sleeve F' to rotate.
 10 Furthermore, owing to this form of rigid construction the fulcrum - screws H², by means of which ways H' are connected to sleeve F', are released from all undue and im-
 15 proper strains and perform only their proper function of swiveling the ways to the sleeve. In these ways slides the adjustable frame H³, connected to the carriage H by screws H⁴. The front end of the frame H³ is slotted, and in the slot lies a segment H⁵, to which the
 20 frame is clamped in any convenient manner, so that the frame H³ may be set at any angle to the carriage and the ways H' will adjust themselves to the angle of the frame H³. I prefer to use for the purpose a hook-bolt,
 25 which lies in the end of the frame H³, one edge of which engages the segment H⁵, the nut H⁶ serving as a clamp-nut. Such being the construction, it will be seen that the reciprocation of the carriage H will also recip-
 30 rocate the frame H³, which will serve as inclined planes to lift the ways H', and consequently the sleeve F', as they move to the left (see Fig. 2) and allow them to fall as the slide moves to the right. The segment may
 35 be marked off with any desired scale, and the frame H³ may thus be set to lie parallel to said carriage, in which case the tool-holder will not reciprocate, or it may be set at any desired angle to the carriage, or preferably
 40 the scale instead of degrees may be in units, which will indicate the length of reciprocation of the tool-holder. To counteract the weight of the various parts, and so render the lifting of the tool-holder more easy of accom-
 45 plishment, I connect the sleeve F', by means of a link J, with a rocking frame hung in brackets J', attached to one end of the case. The links J connect the sleeve with the long arm j of the frame, the short arm j' being
 50 connected by the links j² with a spring j³, running to the other end of the case, where it is provided with a pin j⁴, which rests in a hook j⁵, hanging from the interior of the case. A rocker-shaft j⁶ connects the arms j and j'.
 55 The spring is preferably provided with a thickened extension j⁷, through which passes an adjusting-screw j⁸, by which the spring may be adjusted to the strength desired.

In addition to the parts above described
 60 the machine has a belt-shipper B⁵ of ordinary construction on the end of the rod b, which is mounted in bearings b', projecting from the walls of the case. The shipper is thrown by means of a grooved piece b² on the rod b. In
 65 the groove of this piece works a pin b³, at-

tached to a disk b⁴, carried on the end of the shaft b⁵, which passes out through one wall of the case and has a handle b⁶, by the turning of which the shipper may be moved to throw the belt from one of the pulleys B' B² to the other. Suitable stops are provided to limit the throw of the shipper.

A clutch K of ordinary construction is used to connect and disconnect the cone-pulley D' from the counter-shaft D. This clutch 75 slides upon the shaft D and is moved by the arm k, carried on the end of a slide-rod k', having a grooved piece k², in the groove of which works a pin k³ on the disk k⁴, carried in a shaft on the end of which is the handle k⁵. 80 Turning the handle one way or the other throws the clutch in or out, as the case may be, and connects or disconnects the cone-pulley with the shaft. Stops are also provided in this case to limit the throw of the handles k⁵. 85

The grinder C is preferably an emery-wheel on the end of a shaft C', which runs in bearings C², preferably supported in such manner that the grinder may be moved toward and from the work or laterally to one side or the other of the axis of the work. In order to adjust the grinder laterally, the support C³ for the bearings C² is mounted in ways c on a carriage L, the ways c running parallel with the axis of the shaft C'. By means of a screw 90 passing through a threaded projection C⁴ on said carriage and engaging the support C³ the position of the support C³ on the carriage L may be changed in a way which will be easily understood.

The carriage L may be adjusted to feed the grinder to or from the work by the following means: The carriage L is mounted in ways on the platform A' on top of the case, and it has a nut l, through which runs the threaded 105 end of a rod l'. The farther end of this rod l' carries a hand-wheel l² and is supported in bearings in a casing M, this rod having a longitudinal passage m¹⁰ drilled into it. The casing M also contains a gear l³, which turns 110 freely on the rod l', except when bound there-to by a clutch. Such a clutch is shown at l⁴ as a cone which enters a recess in the gear l³ and may be caused to engage the gear by means of a clutch-rod l⁴, located in the pas- 115 sage m¹⁰ and rigidly attached by a pin l⁶ to the clutch l⁵, the clutch-rod carrying a nut l⁸ on its outer end which is threaded. Upon turning the nut against the hand-wheel l² the clutch is bound against the gear. The rod l' 120 is slotted at l⁵, and the pin l⁶ passes through the slot, the slot being long enough to allow some little play of the pin therein and yet being narrow, so that the gear will communicate motion through the pin to the rod l' 125 when the clutch is engaged.

When the clutch is not engaged with the gear, the rod l' may be turned by the hand-wheel l² to roughly adjust the position of the grinder. When the clutch and gear are en- 130

gaged, however, the grinder can only be adjusted through the instrumentality of gear which is automatically moved in a way now to be described during the operation of the 5 machine.

A worm m engages the gear l^2 and is turned by means of a ratchet-clutch of peculiar character, (see Figs. 7 and 8,) comprising a chambered wheel m' , fast on the shaft m^2 , on 10 which is the worm m . The wheel m' is enclosed in a casing of which one portion—a disk m^3 and a rim m^4 —are fast on the casing M . The other wall is a disk m^5 , free to turn on the shaft m^2 . On the interior of this disk m^5 are 15 mounted two pawls m^6 , each flexibly controlled by a spring m^7 and adapted to engage the inner rim of the wheel m' and turn it when movement is given to the disk m^5 , as below described. The wall m^3 may have similar 20 pawls to act as holding-pawls to keep the wheel from retreating. These pawls work in opposite sides of the wheel.

A pin M' , extending from the exterior of the disk m^5 , is connected by a link M^2 with a 25 segment M^3 , in which is a T-slot, in which the end of the link M^2 may be adjusted by a suitable screw. One end of this segment M^3 is attached to a shaft M^4 , which passes through a bearing in the wall of the casing and carries on its inner end an arm M^5 , the free end of which rests on a stop M^6 . This construction is such that by oscillating the free end of the arm M^5 the worm m will be turned and the grinder C will be fed gradually, the upward movement of the arm M^5 feeding the 30 grinder, the downward movement being ineffective. The arm is lifted by means of a roll M' , mounted on a stud on the gear d^5 . By means of this adjustment the grinder may 35 be moved a comparatively long or short distance, according to the needs of the work. When finishing the edge of the tool, for example, a very fine feed is desired, while if the tool is dull and needs considerable grinding a 40 heavier feed may be used at first. The experience of the operator will teach him as to this. By this adjustment, however, the feed may be made appreciable to the eye or it may be reduced to an almost infinitesimal quantity. 45

I provide a gage by means of which to set the tools at the proper height with relation to the grinder. This consists of an arm N , attached to the end of a vertical rod n by a 50 thumb-screw n' , this rod being adjustably supported by a set-screw n^2 in a socket n^3 on top of the case. The gage is set so that when its arm extends over the tool and the points of the tool touch it the beveled edge 55 of the tool will stand in proper relation (preferably approximately parallel) to a portion of the periphery of the wheel. When the gage is once set, its position does not ordinarily require to be altered except as its arm is 60 swung over the tool-holder in placing a tool

in the machine or out of the way again to allow the grinding operation to take place. The height of the tool is adjusted by raising or lowering the shank F^4 , unscrewing the set-screw F^6 for the purpose. 70

By reference to the foregoing the details of the operation of my machine will now be described. By reference to the drawings it will be seen that the counter-shaft D passes entirely through the machine and projects 75 through the casing on the front side and is supported in the bushing shown. This projecting portion of the shaft D is squared, as shown, for the purpose of receiving a handle by which it may be turned by hand, said 80 handle being easily applied or removed. Now to operate the machine the handle k^5 is turned to withdraw the clutch K from its connection with the pulley D' . The handle above mentioned is now applied to shaft D 85 and the machine turned by hand until the vertical shaft F is brought to its lowest position. (See Fig. 2.) The set-screw F^6 in the shaft F , as stated above, will now stand either to or from the grinder. The nut H^6 on 90 the frame H^3 is now loosened and the frame H^3 set at the required angle by means of the graduations on the arc H^5 and the nut H^6 again set up. Now the shank F^4 of the proper tool-holding chuck is placed within 95 the bore of the shaft F , and as the set-screw F^6 is set into the semicircular groove F^5 the platform f^2 will hold the before-mentioned pin y in the same vertical plane as the groove F^5 . Now when the cutter f^5 is placed on the 100 platform f^2 and the nut f^3 screwed down the pin in the platform and the hole in the cutter before mentioned will cause the extreme points of the cutter to lie in the same vertical plane as the set-screw in the shaft F , thus 105 properly locating the cutter upon the platform. This arrangement, together with the gage N , enables the cutter to be set correctly immediately and without trouble. The screw n' is now loosened and the gage 110 N swung over the points of the cutter, and the set-screw F^6 being again loosened the shank F^4 is raised until the points of the cutter f^5 meet the under surface of the gage N , when the set-screw F^6 is again set up. The gage 115 N is now swung back and secured by screw n' , and the handle is removed from the shaft D . Also by this arrangement a cutter once 120 ground can be replaced upon the machine for resharpening, and the grinder will at once fall right in upon the surface formed at the previous grinding and follow it precisely. Thus it is only necessary to grind just enough 125 to bring up a new keen edge, economizing both time and cutter. These parts are always in adjustment and do not need to be altered, even though the size, shape, or length of the cutter should be changed. After the machine is set as above described 130 a half-turn of the handle b^6 starts the grinder 135

in motion. Next a half-turn of the handle k^5 starts motion of the cutter. Now by means of hand-wheel l^7 the grinder C is caused to approach the cutter f^5 until contact occurs, 5 when a turn of the feed-nut l^8 puts all parts in automatic action, the rate of feed being adjusted by adjusting the position of the link M^2 in the segment M^3 .

As is stated above, the depth of the **V** in 10 the sides of the tool f^5 is dependent upon the vertical stroke which is given to the tool, and this is dependent upon the angle at which the arm H^3 is set to the carriage which supports it. This adjustment may be changed by 15 loosening the nut H^6 and setting the frame H^3 to any desired point on the segment, which preferably carries a scale indicating the height in fractions of an inch to which the tool will be lifted with each reciprocation of 20 the carriage.

I have shown in the drawings the best form 25 of my invention now known to me; but I realize that it may be embodied in other mechanisms by which the essential movements may be given to the tool-holder and grinder. My machine, however, is small and compact and has proved its value for the purpose intended.

What I claim as my invention is—

1. In a machine for grinding a rounding- 30 tool provided with a serrated or **V**-shaped cutting edge, a continuously-rotary tool-holder for grasping and holding the said tool by the non-cutting end or edge thereof, a rotary grinder and means for reciprocating said grinder and tool-holder with relation to one another whereby the grinder may continuously follow the toothed or serrated edge of said tool as it is turned by the tool-holder.

2. In a machine for grinding a rounding- 40 tool provided with a serrated or **V**-shaped cutting edge, a continuously-rotary tool-holder for grasping and holding said tool by the non-cutting end thereof, a rotary grinder and means for reciprocating said tool-holder whereby the cutting edge of said tool is made 45 to describe a path of movement corresponding with the shape of the tooth or teeth and the same is presented continuously to the edge of said grinder.

3. In a machine for grinding a rounding- 50 tool provided with a serrated or **V**-shaped cutting edge, a continuously-rotary tool-holder for grasping and holding said tool by the non-cutting end thereof, a rotary grinder, 55 means for reciprocating said tool-holder whereby the cutting edge of said tool is made to describe a path of movement corresponding with the shape of the tooth or teeth and the same is presented continuously to the edge of said grinder, and means for automatically and positively changing the operative position of said grinder.

4. In a machine for grinding a rounding- 60 tool provided with a serrated or **V**-shaped cutting edge, a continuously-rotary tool- 65

holder for grasping and holding said tool by the non-cutting end thereof, a rotary grinder, means for reciprocating said tool-holder whereby the cutting edge of said tool is made to describe a path of movement corresponding 70 with the shape of the tooth or teeth and the same is presented continuously to the edge of said grinder, and means for adjustably determining the amount of said reciprocation. 75

5. In a tool-grinding machine, a continuously-rotating tool-holder, a rotary grinder, means for reciprocating the one with relation to the other, and means for intermittently feeding the one toward the other. 80

6. In a tool-grinding machine, a continuously-rotating tool-holder, a rotary grinder, means for reciprocating said tool-holder, means for adjustably determining the amount of its reciprocation, and means for 85 intermittently changing the operative position of said grinder.

7. In a tool-grinding machine, a continuously-rotating tool-holder, a rotary grinder, means for reciprocating said tool-holder in a 90 line parallel with the axis of its rotation, means for intermittently feeding said grinder for changing the operative position of the same, and means for adjustably determining the amount of said feed. 95

8. In a tool-grinding machine, a continuously-rotating tool-holder, and a rotary grinder, and means for reciprocating the one with relation to the other in a line parallel to the axis of rotation of the tool, as set forth. 100

9. In a tool-grinding machine, a continuously-rotating tool-holder and a rotary grinder, and adjustable means for reciprocating the tool holder and grinder with relation to each other and in a line parallel to the axis of rotation of said tool-holder, as set forth. 105

10. In a tool-grinding machine, a rotary tool-holder, and a rotary grinder, and means for reciprocating said tool-holder comprising 110 an angular frame adapted to be reciprocated at right angles to the axis of the tool-holder, and means connecting said angular frame with the tool-holder, as described.

11. In a tool-grinding machine a rotary 115 tool-holder and a rotary grinder, means for reciprocating said tool-holder comprising a slide moving at right angles to the axis of said tool-holder and carrying an inclined frame adapted to engage said tool-holder, as 120 and for the purposes described.

12. In a tool-grinding machine a rotary tool-holder, a rotary grinder and means for reciprocating said rotary tool-holder in a line parallel with its axis comprising a horizontal 125 reciprocating carriage, an inclined frame carried thereby, the angle of its inclination being adjustable with relation to the carriage, said inclined frame being adapted to engage said tool-holder, as set forth. 130

13. In a tool-grinding machine a rotary tool-holder and a rotary grinder, and means for giving said tool-holder a movement parallel with its axis comprising a carriage and 5 means for connecting said carriage and said tool-holder and means for reciprocating said carriage comprising a slide adapted to move in a direction parallel with said carriage and connections between said slide and said carriage whereby a movement of the one will cause a corresponding parallel movement of the other, and means for operating said slide, as described. 70
14. In a tool-grinding machine a rotary tool-holder, a rotary grinder, and means for automatically reciprocating said tool-holder in a line parallel with its axis comprising a carriage moving at right angles to the axis of 15 said tool-holder and means connecting said carriage and said tool-holder, whereby the movement of said carriage will cause the reciprocation of said tool-holder, and means for reciprocating said carriage, comprising a slide, connections between said slide and said 20 carriage whereby the movement of the one will cause a corresponding parallel movement of the other, and a cam, and connections between said cam and said slide whereby the rotation of said cam will cause the reciprocation 25 of said slide, as set forth. 80
15. In a tool-grinding machine a rotary grinder, and a rotary tool-holder, and means adapted to cause the reciprocation of said tool-holder comprising pivoted ways mounted 30 on the sides of said tool-holder, a carriage and means for reciprocating it at right angles to the axis of said tool-holder, a frame connected to said carriage and adapted to run in said ways, and means whereby said frame is 35 set at a predetermined angle to said carriage, as set forth. 90
16. In a tool-grinding machine, a tool-holder comprising a shaft, a sleeve surrounding and supporting said shaft, means for rotating said shaft within said sleeve, and means 40 whereby said sleeve and said shaft may be moved together in a line parallel with the axis of said shaft, as described. 100
17. In a tool-grinding machine, a tool-holder comprising an adjustable shank, a shaft carrying said shank, a sleeve surrounding said shaft, and means whereby said shaft is rotated in said sleeve, and said sleeve and shaft are reciprocated in combination with a 45 rotary grinder, as described. 110
18. A tool-grinding machine having a tool-holder, means whereby said tool-holder may be reciprocated, said means comprising a carriage having a movement at right angles to 50 the axis of said tool-holder, and yielding means tending to counteract the weight of said tool-holder, as described. 120
19. In a tool-grinding machine, a tool-holder, a horizontally-moving carriage sup-

porting said tool-holder, and means whereby 65 the movement of said carriage is communicated to and results in a vertical movement of said tool-holder, and yielding means whereby the weight of said tool-holder is more or less counteracted, as described. 70

20. In a tool-grinding machine, a tool-holder adapted to be reciprocated, a carriage adapted to be moved horizontally, connections between said carriage and said tool-holder whereby said tool-holder will be reciprocated vertically, and means for counterbalancing the weight of the vertically-moving parts, comprising a rocking frame, means for connecting said rocking frame with said tool-holder, and a lifting-spring connected to said 80 rocking frame, as and for the purposes described. 75

21. In a grinding-machine, a tool-holder adapted to be reciprocated vertically, horizontal ways, a carriage adapted to run in said ways, connections between said carriage and said tool-holder whereby said tool-holder will be reciprocated with the reciprocation of said carriage and at right angles thereto, a rocking frame connected to said tool-holder, and a spring adapted to lift said tool-holder, one end of said spring being connected with said rocking frame, means for supporting the other end of said spring, and means for adjusting its tension, as described. 95

22. In a grinding-machine, a rotary grinder, a tool-holder and means whereby said tool-holder is rotated and reciprocated in a line parallel with its axis of rotation, and means whereby said grinder is fed toward and 100 from said tool-holder, as described. 100

23. In a grinding-machine, a grinder mounted on a carriage, said carriage being provided with an adjusting-nut, a screw passing through said nut, means whereby 105 said screw is rotated, a tool-holder, and means connecting said tool-holder with said screw-rotating means, whereby the movements of said tool-holder will cause the feeding of said grinder, as set forth. 110

24. In a grinding-machine, a grinder mounted on a carriage, said carriage being provided with an adjusting-nut, a screw passing through said nut, means whereby said screw is rotated, a tool-holder, and means whereby 115 said screw-rotating means is operated to feed the carriage automatically and said tool-holder is reciprocated, as set forth. 120

25. In a tool-grinding machine, a rotary tool-holder, a rotary grinder, a feed adapted 120 to feed said grinder toward said tool-holder, and means connecting said grinder and said tool-holder, whereby the rotation of said tool-holder and the feed of said grinder will take place simultaneously, as described. 125

26. In a grinding-machine, the grinder mounted upon a carriage, means for adjusting said carriage, and also for feeding said

carriage, said means comprising a nut attached to said carriage, a screw working there-in and common to both feeding and adjusting mechanisms, an automatic mechanism 5 adapted to be connected with said screw to turn it, a hand turning mechanism also adapted to be connected to said screw and a clutch connecting said screw and said automatic turning mechanism whereby by disengaging 10 said clutch the turning of said screw may be accomplished by hand and upon engagement of said clutch the turning of said screw will be accomplished automatically, as described.

27. In combination with a rotary tool- 15 holder and a grinder, a feeding mechanism for said grinder comprising a feed-screw, a gear free to turn thereon and forming one member of a clutch mechanism, a second member of said clutch mechanism connected with said 20 feed-screw to turn therewith, and means whereby said clutch and said gear are clamped together, as set forth.

28. In combination with a rotary tool- 25 holder and a grinder, a feeding mechanism for said grinder comprising a feed-screw, a gear free to turn thereon and forming one member of a clutch mechanism, a second member of said clutch mechanism connected with said 30 feed-screw to turn therewith, and means whereby said clutch and said gear are clamped together, said means comprising a clutch-rod entering the end of said feed- 35 screw and pinned therein, and capable of a limited longitudinal movement with relation thereto, a clutch member attached to said clutch-rod, and a set-nut on said clutch-rod

adapted to bind said clutch member against said gear, as described.

29. In a tool-grinding machine, a tool- 40 grinder and means whereby it is fed automatically toward and from the tool comprising a feed-nut, a screw, a gear mounted on said feed-screw, a worm engaging said gear, and means for giving said worm an intermittent rotary motion, a rotary tool-holder, and 45 means connecting said tool-holder and said intermittent worm-rotating means whereby it is operated, as described.

30. In a tool-grinding machine, means for 50 feeding said tool-grinder comprising a feed-screw, a gear mounted thereon, a worm adapted to engage said gear, a clutch on said worm, means for operating said clutch to rotate said worm intermittently comprising a rocking frame, and means whereby said rocking 55 frame is rocked, and an adjustable connection between said rocking frame, and said clutch, as set forth.

31. In a tool-grinding machine, a tool- 60 grinder mounted on the carriage, means for feeding the said carriage comprising a screw, a gear upon said screw, a worm engaging said gear, a wheel located on the worm-shaft, a disk free to turn on said shaft, pawls connecting said disk and said wheel, and a rocking 65 frame, and means whereby it is rocked, and means for adjustably connecting said rocking frame with said disk, as described.

J. GEORGE POOL.
